BAT REVERSING LINT CLEANER

Hoyle G. Moss, Lubbock, Tex., assignor of one-fourth to Ennis E. Moss, Sr., one-fourth to Ennis E. Moss, Jr., and one-fourth to James P. Moss, all of Lubbock, Tex.

Application January 4, 1957, Serial No. 632,452.

8 Claims. (Cl. 19—67)

This invention relates to a cleaner for lint cotton, of the type which handles the cotton in the form of a thin bat, preferably drawing the bat to extreme thinness by passing it between successive pairs of drawing instrumentalities driven at progressively higher speeds, and presenting the thinly fringed end edge of the bat to a rapidly revolving, toothed cylinder which continually combs off the fringe and carries it around in centrifugally extended attitude into operative contact with cleaning instrumentalities such as grid bars, by means of which motes and other trash are removed. This type of lint cleaner is exemplified in the one forming the subject of my pending patent application Serial No. 616,042, filed October 15, 1956.

The general object of the present invention is to provide a lint cleaner having two toothed cylinders directly tangentially related, providing a transfer point for the bat from one cylinder to the other, the transfer creating reversal, with respect to which side of the bat is presented to the cleaning instrumentalities associated with each cylinder, the outer side of the bat on the anterior cylinder becoming the inner side on the cylinder to which the bat is transferred.

Another object of the invention is to provide a lint cleaner of the type described, in which substantially identical cleaning treatment is accorded to both sides of the bat, and the lint prevented from becoming centrifugally detached from the teeth of the cylinders and lost with the trash, through the provision of bars extending transversely across each cylinder close to the point at which the cotton is received by the respective cylinders, one of the functions of which bars is to seat the cotton firmly in the teeth of the respective cylinders, and the provision of a set of grid bars for each cylinder on opposite sides of the diametrical plane through the axes of said cylinders and at point of cotton transfer, the grid bars being spaced from the respective transversely extending bars and from each other adequately close to give insufficient time for the cotton to become centrifugally detached.

A further object of the invention is to provide means throughout the path of movement of the cotton through the cleaner, to suppress spurious air currents which conflict and create turbulence with consequent napping of the lint.

Other objects of the invention will appear as the following description of a practical and tried embodiment thereof proceeds.

In the drawing which accompanies and forms a part of the following specification:

Figure 1 is a vertical section through a lint cleaner, embodying the principles of the invention;

Figure 2 is a side elevation of the resilient mount of the feed bar, parts being broken away and parts being shown in section;

Figure 3 is a sectional view taken along the line 3—3 of Figure 2;

Figure 4 is a fragmentary elevational view of the resilient mount for the diverting bar;

2

Figure 5 is a view in section, taken along the line 5—5 of Figure 4.

Referring now in detail to the drawings, the illustrated embodiment of the subject invention comprises a casing 5 having parallel sides, one of which is shown at 2, and being otherwise shaped as shown. Journaled on bearings in the parallel walls are the principal rotatable elements of the cleaning system. The upper end of the casing is adapted to have a standard condenser or any other type of condenser which collects the cotton in bat form, mounted upon it. Successive spaced pairs of cooperating drawing rolls 3 and 4 are mounted in the casing adjacent its upper end. Cotton in bat form is fed into the space between the rolls of the upper pair without vehicle air, the bat extending downward bridging the space between the pairs of rolls and passing between the rolls of the lower pair, the latter rolls being driven at a higher speed than the rolls above it so as to draw the bat thinner. It is further thinned by passing through the narrow space between the feed bar 5 and a cooperating corrugated feed roll 6. The feed bar 5 has a smooth curved face 7, the lower part of which is curved concentric to the periphery of the roll 6, along which face the bat is slidably advanced by the rotation of the roll 6, its lower end reduced to a fringe by the drawing, being fed downwardly over the nose 8 of the feed bar into the path of the teeth of an underlying toothed cylinder 9, the upper arc of the periphery of which rotates toward the feed bar so that the bat is bent abruptly about the nose 8 through the stress engendered by its engagement with the teeth, the latter continuously combing the fringe off of the transcending bat and carrying it around first beneath the lower face 10 of the feed bar, and then past the series of grid bars 11.

35 The nose of the feed bar acts as a purchase for the part of the bat engaged by the teeth of the cylinder 9, relieving that part of the bat which extends upwardly from the nose, from much of the strain incident to the detachment of the fringe. Inherently, the bat is subject to thin spots, and therefore, it cannot at all times be uniformly tensioned throughout the extent of its width between the feed bar and feed roll 6, so that the pull of the teeth tends to tear off the thinner and less firmly held portions of the bat up into the region between the feed bar and feed roll. The change in direction of the bat about the nose 8 resolves the pulling force of the teeth into components, the one which pulls downwardly upon that part of the bat between the feed bar and roll 6 being relatively small. The feed roll is resiliently mounted by means which will later be described, so that it presses the bat yieldingly toward the face 7 and can yield to the passage of the thick places in the bat, so that resistance to normal descent of the bat will not ordinarily build up to the point at which the bat becomes torn by the pull of the teeth.

55 The lower face 10 of the feed bar lies almost contiguous to the teeth of cylinder 9 at its forward end, and slopes up slightly toward the rear, its function being to firmly set the cotton in the teeth. The lint may be envisioned as a loop having its bight at the fore embracing the tooth, and having free end portions trailing toward the rear. The free end portions have very little weight unless loaded with a mote or other trash particle, so that if clean they do not stand out very far under centrifugal force, but if they are so loaded, they may fly out as they emerge from beneath the feed bar and from beneath the grid bars, with sufficient force to be ejected from the teeth and lost with the trash. This statement is a simplification of what actually goes on, for the lint fiber as a rule does not act independently, but in coherence with other fibers, forming a lock. The lower face 10 of the feed plate is made to flare at a small angle away from the periphery of the

toothed cylinder so as to release the trailing ends of the lint fibers gradually, rather than have them fly out suddenly, with the risk of the loops becoming detached from the teeth.

The main function of the grid bars is, of course, to comb the centrifugally extended lint and remove the motes and trash adherent thereto. Since the extended ends of the fibers strike the convergent edges of the grid bars quite impactively, the trash is thrown off through its inertia.

Another function of the series of grid bars is to keep the cotton from becoming detached centrifugally from the toothed cylinder while being cleaned. For the performance of this function the grid bar adjacent the feed bar 5 is spaced sufficiently close to the feed bar to take charge of the lint before it has had time to fully extend itself radially under centrifugal force and flatten it down toward the teeth, and each of the successive grid bars is positioned with corresponding closeness to the one ahead of it. Like the lower face 10 of the feed bar, the lower face of each grid bar adjacent the toothed cylinder flares away from the latter to control the gradual release of the trailing ends of the loops of lint.

It has been found in practice that most of the trash on the side of the bat exposed to the grid bars 11 is removed by the anterior bars of the series, but that a small quantity of subsurface trash is shifted by pressure of the grid bars to the inner side of the bat. It must be kept in mind that the bat is quite thin. This trash will, therefore, be on the outside of the bat when the latter is reversed by its transfer to the complementary toothed cylinder 13, and in position to be removed by the grid bars associated with the latter cylinder.

An arcuate shield 12 hugs the first toothed cylinder 9 from a point adjacent the end of the series of grid bars 11 to a point adjacent the region of substantial tangency of the cylinder 9 to the cylinder 13. This shield is sufficiently close to the periphery of the cylinder 9 to keep the lint seated in the teeth until the point of transfer is reached. Since the arc of the surface of cylinder 9 which said shield circumscribes is loaded with cotton, this cotton fills the space between the shield and cylinder and blocks the passage of the normal circumferential air flow about the periphery of the cylinder which is engendered by the rotation of the cylinder. The shield 12 progressively diverges slightly from the periphery of the cylinder 9 toward the transfer point, so as to permit the cotton between it and the cylinder 9 to open up somewhat as it approaches the doffing point in order to facilitate the doffing.

It will be noted that the casing 1 includes an arcuate shield 14 adjacent the shield 12, which covers a portion of the periphery of cylinder 13 which approaches the transfer point. The part of the periphery overlain by the shield 14 is unloaded, nevertheless, it is instrumental in cutting off the circumferential air flow about the part of the cylinder that it covers, since its lower end terminates in the part 50 of the doffer chamber 49 which lies adjacent the deep pockets 16 between the brushes 17 of the doffer 18. These pockets are under vacuum, due to centrifugal displacement and consequent attenuation of the contained air, which vacuum is not satisfied by induced air through the nozzle 45, due to the rapid rotation of the doffer. Little or no air, therefore, enters beneath the shield 14 from this source, and it prevents the cylinder from entraining air along the quadrantal arc that it covers. If the circumferential air flow toward the transfer point attending both cylinders were not suppressed by the respective shields 12 and 14, the air currents would conflict in the region of the point of transfer, creating turbulence, thereby promoting nepping of the fibers.

However, an air jet is essential at the transfer point between the two toothed cylinders, to assist in the transfer. There is, of course, clearance between the teeth of the cylinders, and the bights of the loops which are the only parts of the fibers that could be caught by the teeth of the

faster moving cylinder are seated deep in the teeth of the other cylinder and not in the path of the faster moving teeth. The ends of the loops that do stand out in the path of the faster moving teeth have been combed out straight by the grid bars, and afford no hold for the faster moving teeth. Only when the slower cylinder is heavily clothed with bat, is it possible for much lint to be removed mechanically. Lint cleaners, such as that of the present invention, which are designed to do a good job upon dirty cotton are made to work upon a thin bat and at high speed, so that each tooth combs off only a small number of fibers. The effective transfer of these makes the air jet indispensable.

In order to provide for this air jet, the shields 12 and 14 are spaced apart at their convergent ends to form the mouth 20 of a longitudinal nozzle defined between the spaced baffles 21 and 21', which nozzle is directed toward the point of lint transfer. The air jet through said nozzle is induced by the vacuum at the surface of the cylinder 13 beneath the shield 14, the velocity of the cylinder 13 carrying the vacuum ahead of the mouth of the nozzle 20. Since the cylinder 13 is moving faster than the cylinder 9, the velocity of the air jet exceeds the peripheral speed of the cylinder 9, the jet overtaking the lint on cylinder 9, loosening the cotton in the teeth of the latter cylinder so as to be readily transferred by the teeth of cylinder 13. The transfer is thus effected by a single air jet tangent to both cylinders, and therefore, free from turbulence, in fact having a further combing action upon the lint. The air jet itself by blowing through and against the lint during the short interval in which the lint is air suspended, exerts a further cleaning action upon the lint. If the problem of prevention of nepping were ignored, the circumferential air between the cylinder 13 and shield 14 would produce a jet adequate to effect the transfer of cotton from one cylinder to the other without the necessity of providing the tangential air jet at 20.

Reference has been made to the feed roll 6 being resiliently mounted. Figure 2 shows the structural nature of this mounting, it being understood that the means which are shown in Figure 2 are duplicated at the opposite parallel walls of the casing and at the opposite ends of the feed roll. The brackets 22 and 23 are bolted to the casing walls, the slots in the pockets permitting adjustment. An arm 24 is pivoted at one end to the bracket 23, which at its other end carries the bearing in which the feed roll is journaled. The driving means (not shown) obviously must be coaxial with the axis about which the arm 24 pivots. A bar 25 is fixed to the arm 24 at a point between its axis of swing and the axis of the feed roll. When the bar swings up, the feed roll swings over toward the feed bar 5. The bracket 23 has an ear 26, through which an adjusting stud 27 is threaded. This adjustability determines the minimum distance between the feed roll and feed plate. The bracket 22 carries a housing 28 containing a spring 29. The housing has oppositely aligned slots 30 and 31, through which the bar 25 extends, passing above the spring 29. When the feed roll is pressed away from the feed bar by an intervening wad of cotton in the bat, the bar 25 presses down upon the spring. The latter returns the bar 25 and feed roll to normal position when the wad has passed, keeping the feed roll pressed against the bat with yielding tension.

A diverting bar 32 extends longitudinally of the cylinders 9 and 13, positioned in the trough defined by the adjacent peripheries of the cylinders at the side of the point of cotton transfer opposite the mouth 20 of the air jet nozzle. Said diverting bar has a nose 33 facing the point of transfer, said nose being deflected so as to lie quite close to the cylinder 9 for the purpose of diverting such cotton as may be free when it reaches said nose, toward the teeth of cylinder 13 and away from the teeth of cylinder 9. The bar 32 has a lower face 34 similarly related to the toothed periphery of cylinder 13 as the face 10

of feed bar 5 is to cylinder 9, and having the same functions.

The diverting bar 32 is resiliently mounted so as to yield to the resistance of relatively thick wads of cotton which may be transferred from cylinder 9 to cylinder 13 and attempt to pass between the bar 32 and the cylinder 13. The structure constituting the resilient mounting illustrated in Figures 4 and 5, which show that the bar 32 is secured to the flanged end of a fitting 54, the opposite end of which is formed with a socket receiving one end of a spring 56. The opposite end of which spring surrounds a retaining boss 57 projecting from the slotted bracket 58, secured to one of the parallel sides of the casing. The fitting 54 includes an upwardly extending curved arm 59 which is pivoted upon the stud 60, secured to the side of the casing. Said stud is mounted in a vertical plane which embraces the nose of the diverting bar. The arm 59 carries an adjustable stud 61 engageable with a stop 62, also fixed to the side wall of the casing. The mode of operation is obvious. When the wad attempts to pass through the restricted space between the lower face of the diverting bar 32 and the periphery of cylinder 13, said bar is pushed backward against the bias of the spring 56 and at the same time, rocked slightly upward through an arc which is substantially concentric with the periphery of cylinder 9. The upward arcuate movement is inconsiderable and of no importance to the invention, the location of the stud 60 at a point eccentric with respect to the axis of the cylinder 9 being a matter of convenience.

The casing 1 is curved to form a shield 35 substantially concentric to the periphery of cylinder 9 and closely embracing the unloaded arc of said cylinder for a distance extending from the diverting bar 32 to a point adjacent the feed roll 6. In the form shown, said shield is secured to the diverting bar 32, and therefore, is resiliently independently of the rest of the casing so as to give with the movement of said bar. A portion of the air from the jet entering by way of the nozzle 20 passes beneath the bar 32, but part of said air jet discharges through the space between the shield 32 and the cylinder 9 into that part of the casing in the vicinity of the pairs of drawing rolls 3 and 4. A flashing 36 is provided between the casing wall and feed roll, including a yielding portion 37 which wipes against the feed roll, which serves the primary purpose of sealing the air which might come around the cylinder and course it directionally tangent to the faces of the feed roller 6 and the saw 9. Actually the bar 32 having its forward nose 33 set very close to the cylinder 9 scalps the air carried by cylinder 9, coursing it downwardly in a circular path following the cylinder 13. It too would serve the purpose of seating the cotton better into the teeth of cylinder 13.

Returning to the discussion of the diverting bar 32, this member is positioned anterior to a second series of grid bars 38, the spacing of which with respect to the bar 32 and to each other is such as to keep the lint firmly fastened in the teeth of the cylinder 13. The grid bars operate upon the face of the bat opposite to that which was contacted by the grid bars 11, and removes practically all of the remaining trash from the lint. The trash thrown off by the grid bars 38 gravitates into a trash pan 39 formed as a lower part of the casing, and which is connected to a suction duct, not shown. The trash removed by the grid bars 11 falls upon a trash belt 40, which carries the trash outside the casing and may deliver it to the suction duct that serves the trash pan.

The toothed cylinder 13 is underlain by an arcuate shield 41, which lies sufficiently close to said cylinder to maintain the cotton seated in the teeth of the cylinder and by virtue of the presence of the cotton between said shield and the cylinder, to block the circumferential flow of air to the doffing point 42. The shield 41 at one end is joined to a partition 43, which confines the trash from the grid bars 38 to that part of the casing to the

right of said partition, as viewed in Figure 1. The opposite end of the shield is formed with a baffle 44 in a plane tangent to the cylinder 13 at the doffing point, said baffle constituting one side of an atmospheric air nozzle 45, drawing clean air from that part of the casing to the left of the partition 43, the opposite side of the nozzle being a similar baffle 46 parallel to the baffle 44. The baffle 46 is formed at the anterior end of a shield 47 which underlies the doffer 18.

- 10 Said doffer, as shown, is of the conventional brush type, being a drum provided about its periphery with a circumferential series of longitudinally extending spaced brushes 48, forming the deep pockets 16 previously referred to, and which are continuously under suction, due to centrifugal displacement of the contained air. The adjacent ends of the shields 41 and 47 are so spaced as to leave exposed an appreciable portion of the periphery of the cylinder 13, to that part of the casing which defines the doffing chamber 49, of which chamber the shield 47 forms a boundary wall. The actual doffing point is at the intermediate part of this exposed portion. The space between the shield 41 and the cylinder 13 decreases in spacing slightly so as to restrict the movement of air generated by saw 13 from entering the doffing point 42. As the cotton leaves the adjoining faces of shield 41 and 45, the cotton opens abruptly and is easily doffed.

The vacuum persisting in the pockets 16 is the moving force that induces an air jet through the nozzle 45. Since the peripheral speed of the doffer is greater than that of the toothed cylinder 13, the air jet overtakes the cotton on the teeth of cylinder 13 and materially assists the brushes in taking off all of the lint. The air jet, beyond the point of tangency, is diverted from its straight course to flow in a path circumferentially of the doffer, but outside of the path of the ends of the brushes, due to centrifugal exclusion from the pocket 16, and said circumferential air flow is the vehicle which carries the lint toward the lint discharge duct 51. The underlying shield 47 has an adjustable gate 52 at its posterior end, which is ordinarily adjusted with respect to the brushes so as to direct the circumferentially traveling air flow toward the lint duct and keep lint from following the doffer around within the shield 47 toward the doffing point. The wall of the doffing chamber is provided with an air intake opening 53 near its top, and preferably above the lint duct. The circumferentially diverted air jet entrains auxiliary air through said air intake 53, the downward direction of the entrained air assisting in conducting the lint into the lint duct without creating turbulence in the doffing chamber. The air intake 53 also provides an emergency outlet for the cotton, should some eventuality arise that may interrupt the flow of cotton from the lint duct, resulting in the cotton backing up in the doffing chamber. When this happens, and the circumferential air flow can no longer exhaust into the lint duct, it selectively reverses its normal flow path and discharges the lint through the air intake 53 into a pan, not shown, or other receptacle provided to receive it.

While I have in the above description defined a practical embodiment of the invention, it will be understood by those skilled in the art that the specific details of construction and arrangement of parts, as shown, are by way of example and not to be construed as limiting the scope of the invention.

65 What I claim is:

1. Cleaner for lint cotton of the type adapted to be supplied with cotton in the form of a bat, comprising a pair of toothed cylinders one above the other arranged tangentially and driven in opposite directions, the lower cylinder having greater speed whereby cotton is transferred directly from the upper to the lower cylinder at the point of tangency, the faces of the bat being reversed incident to the transfer, means anterior to the upper cylinder for drawing the supplied bat and feeding the thinned end thereof to said cylinder in the upper arc of its path

of rotation, said means including a feed bar having a face thereof positioned sufficiently close to the upper cylinder to seat the cotton on the teeth of said upper cylinder, a nozzle between said cylinders for directing a jet of air substantially tangent to said cylinders at the point of transfer for effecting transfer of the cotton, a diverting bar between said cylinders on the side of the transfer point opposite said nozzle, said diverting bar having a portion sufficiently close to said upper cylinder to divert cotton in the course of its transfer from said upper cylinder to said lower cylinder, said diverting bar having a lower face sufficiently close to said lower cylinder to seat the transferred cotton in the teeth of said lower cylinder, and upper and lower series of grid bars arranged about the peripheries of the respective upper and lower cylinders in the direction of rotation of said cylinders, said grid bars being successively spaced sufficiently close to the respective feed bars and diverting bars and to one another to prevent the cotton becoming detached from the teeth of the respective cylinders.

2. Cleaner for lint cotton of the type adapted to be supplied with cotton in the form of a bat, comprising a pair of toothed cylinders positioned one above the other with their axes substantially in a common vertical plane, arranged tangentially and driven in opposite directions, the lower cylinder having the greater peripheral speed whereby cotton is transferred directly from the upper to the lower cylinder at their point of tangency, the faces of the bat being reversed by the transfer, means positioned above the upper cylinder for drawing the supplied bat into a thin web and feeding the end of said web to the periphery of the upper cylinder, said means including a feed bar having a face thereof lying sufficiently close to the upper cylinder to seat the cotton in the teeth thereof, a nozzle between said cylinders for directing a jet of air substantially tangent to said cylinders at the point of transfer for effecting transfer of the cotton, a diverting bar between said cylinders on the opposite side of said vertical plane to said feed bar, said diverting bar having a portion sufficiently close to said upper cylinder to divert cotton in the course of transfer while detached from said upper cylinder, away from the latter and toward said lower cylinder, said diverting bar having a lower face positioned sufficiently close to said lower cylinder to seat the cotton in the teeth of said lower cylinder, and upper and lower series of grid bars about the peripheries of the respective upper and lower cylinders, following said feed bar and diverting bar in the direction of rotation of the respective cylinders, said grid bars being successively spaced sufficiently close to the respective feed bar and diverting bar and to each other to prevent the cotton becoming detached from the teeth of the respective cylinders.

3. Cleaner for lint cotton as claimed in claim 2, said diverting bar being resiliently mounted so as to yield to an intervening wad of cotton on said lower cylinder, the lower face of said diverting bar being upwardly tangent in a forward direction with respect to the adjacent periphery of said lower cylinder to permit wedging entry of the wad beneath said feed bar.

4. Cleaner for lint cotton as claimed in claim 2, including upper and lower arcuate shield means about adjacent peripheral arcs of said upper and lower cylinders, said shield means extending to the mouth of said nozzle and lying close to the teeth of the respective cylinders for suppressing the entrainment of peripherally flowing air by said shielded peripheral portions incident to the rotation of said cylinders, the shield means about the loaded arc preventing passage of air between itself and the upper cylinder, and the shield means about the unloaded arc maintaining vacuum between itself and the peripheral arc that it overlies, which vacuum induces the air jet through said nozzle.

5. Cleaner for lint cotton of the type adapted to be supplied with cotton in the form of a bat, comprising a

casing, upper and lower toothed cylinders mounted in said casing with their axes substantially in a vertical plane, said cylinders being directly tangent, the line of tangency forming a transfer point for cotton from the upper to the lower cylinder, means above the upper cylinder for drawing the supplied bat into a thin web and feeding the end of said web to the teeth of the upper cylinder, said means comprising substantially vertically arranged spaced pairs of drawing rolls between which the bat passes, and feeding instrumentalities between said drawing rolls and the upper toothed cylinder comprising a feed bar and a complementary feed roll, between which said bat, thinned by the drawing, passes, one of said feeding instrumentalities being resiliently mounted to yield with respect to the other for holding said bat and letting pass bat areas of variable thickness, a first series of spaced grid bars following said feed bar, arranged in operative proximity to said upper cylinder, a nozzle at the forward side of said transfer point for directing an air jet tangentially across said transfer point for effecting transfer of the cotton, a diverting bar at the opposite side of said transfer point shaped and arranged to divert the lint detached from the upper cylinder away from that cylinder and toward the teeth of the lower cylinder, said diverting bar having a lower face so positioned as to seat the transferred lint in the teeth of the lower cylinder, said diverting bar being resiliently mounted to yield away from said lower cylinder responsive to the intrusion of thick wads between said diverting bar and said lower cylinder, said casing being formed as a shield about the periphery of said upper cylinder, said shield extending from said diverting bar to the wall of said casing adjacent said feed roll, thereby to prevent the entrainment of peripheral air along the unloaded arc covered by said shield, and a baffle between the wall of said casing and said feed roll to prevent that part of the air jet which exhausts through the space between said unloaded arc and shield from reaching the exposed bridging portion of the bat between said pairs of feed rolls.

6. Cleaner for lint cotton of the type adapted to be supplied with cotton in the form of a bat, comprising upper and lower toothed cylinders with their axes substantially in a vertical plane, said cylinders being directly tangent, the line of tangency forming the point of cotton transfer, bat drawing means and thinned bat feeding means above the upper cylinder, said feeding means including a feed bar at one side of said vertical plane for seating the feed cotton in the teeth of the upper cylinder, a diverting bar above the second cylinder at the opposite side of said vertical plane for seating transferred cotton in the teeth of said second cylinder, a series of lint cleaning bars for each cylinder following the respective feed bar and diverting bar in the direction of rotation of the respective cylinders, a nozzle at the side of said transfer point opposite said diverting bar for directing an air jet across said transfer point to detach the lint from the upper cylinder, and means peripherally shielding arcuate portions of both cylinders adjacent the mouth of said nozzle to suppress conflicting currents that would cause turbulence in said air jet.

7. Cleaner for lint cotton as claimed in claim 6, including a doffer tangent to said lower cylinder, said doffer being of the type creating a vacuum in a region adjacent the doffing point, a nozzle at said doffing point for directing an air jet induced by said vacuum tangentially across said doffing point to assist in the doffing, the shielding means for the lower cylinder extending to the region of vacuum whereby vacuum is drawn at said transfer point which induces the air jet from the first mentioned nozzle.

8. Cleaner for lint cotton of the type adapted to be continuously supplied with cotton in the form of a bat, said cleaner including a casing housing the following instrumentalities, a pair of tangent oppositely rotatable toothed cylinders, the point of tangency being the point

at which the bat is transferred and the exposed side thereof reversed, means for feeding the bat to one cylinder, means for doffing lint from the other cylinder and cleaning means in operative proximity to both cylinders, a nozzle at one side of the transfer point for directing an air jet upon the lint at the point of transfer to assist in effecting the transfer, a diverting bar at the side of said transfer point opposite said nozzle for diverting lint from the cylinder from which it has become detached and seating it in the teeth of the cylinder to which it is being transferred, means for resiliently mounting said diverting bar comprising a pair of similar arms pivotally mounted coaxially at opposite sides of said casing, each terminating at its opposite end in a block, means securing said diverting bar to the forward ends of said blocks, the opposite ends being socketed, brackets fixed to said casing at opposite sides, bosses carried by said brackets axially

10
15

aligned with said sockets, springs having their opposite ends respectively in said sockets and surrounding said bosses, biasing said feed bar toward said cylinders, stops fixed to said casing at opposite sides, and adjustable studs carried by said arms engageable with said stops for determining the minimum distance between said diverting bar and said cylinders.
